ATTORNEY.

UNITED STATES PATENT OFFICE.

WILLIAM E. BROCK, OF PLAINFIELD, NEW JERSEY.

MECHANICAL MOVEMENT.

SPECIFICATION forming part of Letters Patent No. 427,038, dated May 6, 1890.

Application filed September 7, 1889. Serial No. 323,270. (No model.)

To all whom it may concern.

Be it known that I, WILLIAM E. BROCK, a citizen of the United States, and a resident of Plainfield, in the county of Somerset and State 5 of New Jersey, have invented certain new and useful Improvements in Mechanical Movements, of which the following is a specification.

My invention is a mechanical movement for 10 imparting rotary motion to a crank; and it consists of the novel devices hereinafter described for automatically adjusting a movable fulcrum for one of two levers in relation to the crank-axis, so that a comparatively 15 short throw of the main lever is required for operating the crank.

In the accompanying drawings, Figure I represents a sectional elevation of a mechanical movement embodying my invention. 20 Fig. II represents a plan view thereof.

Similar letters of reference indicate similar parts.

The letters A B indicate two sets of levers, each having a bar A' or B' at one end, connecting the levers of the respective sets to each other, for adapting said levers to be operated, one set by the hands and the other by the feet. C indicates a double crank, to which both of said levers are connected by means of 25 rods or pitmen A² B², the latter extending from the crank-pin to an intermediate portion of the levers.

D indicates a swinging arm, which carries a pivot D', forming a fulcrum for the main or 30 hand lever A, said arm being hung on a stud D², and F indicates a shaft forming a fulcrum for the foot-lever B. Said shaft F is mounted in a frame G, and thus is in a fixed position, in contradistinction to the pivot D', 35 which, being arranged on the swinging arm D, is movable.

I indicates a rod extending from an intermediate portion of the swinging arm D to one end of the foot-lever B, for connecting said 40 arm with the lever.

In the frame G are also mounted the stud D² and a shaft C', carrying the double crank C, while above said frame is arranged a seat J, in a suitable position to enable the occupant to reach the bars A' B' with the hands 50 and feet, respectively, for operating the levers.

In the operation of said levers A B the swinging arm D is put in motion through the rod I, causing the pivot D' to move in a direction toward and from the axis of the crank C, and 55 due to this adjustment of said pivot the hand-lever A is brought to varying distances from said crank during its oscillating motion, with the effect of reducing the degree of such motion required to operate the crank. In other 60 words, by said automatic adjustment of the pivot D' a crank of large radius may be operated by a comparatively short throw of the lever A, and a great amount of power is obtained with the least expenditure of manual 65 force.

What I claim as new, and desire to secure by Letters Patent, is—

1. A mechanical movement consisting of a double crank, two levers connected to said 70 crank by suitable rods, a movable and a fixed fulcrum for said levers, respectively, and a means for connecting the movable fulcrum to the lever having the fixed fulcrum, whereby the movable fulcrum is automatically adjusted 75 relatively to the crank-axis, as and for the purpose described.

2. A mechanical movement consisting of a double crank, a hand-lever and foot-lever, both connected to said crank by suitable rods, 80 a swinging arm carrying the fulcrum for the hand-lever, a fixed fulcrum for the foot-lever, and a rod connecting said arm with the foot-lever, substantially as and for the purpose described.

WILLIAM E. BROCK.
